H. E. & W. P. MATTHEWS.

CAR REPLACER.

APPLICATION FILED MAY 28, 1907.

UNITED STATES PATENT OFFICE.

HENRY EDWARD MATTHEWS AND WALTER PETER MATTHEWS, OF SALIDA, COLORADO.

CAR-REPLACER.

No. 878,409.

Specification of Letters Patent.

Patented Feb. 4, 1908.

Application filed May 28, 1907. Serial No. 376,051.

To all whom it may concern:

Be it known that we, HENRY EDWARD MATTHEWS and WALTER PETER MATTHEWS, both citizens of the United States, and residents of Salida, in the county of Chaffee and State of Colorado, have invented a new and Improved Car-Replacer, of which the following is a full, clear, and exact description.

This invention relates to car replacers such as used in replacing derailed cars upon the track.

The object of the invention is to produce a replacer of simple construction, formed in such a way as to facilitate its being held in position when in use, and to provide a form for the outside replacer which will facilitate the passing of wheels over the device which have not become displaced from the track.

The invention consists in the construction and combination of parts, to be more fully described hereinafter and particularly set forth in the claims.

Reference is to be had to the accompanying drawings forming a part of this specification, in which similar characters of reference indicate corresponding parts in all the figures.

Figure 1 is a plan showing the two replacing devices in position upon a track, the rails and ties of which are indicated in dotted outline; Fig. 2 is a bottom plan view of the inside replacer; Fig. 3 is an inside elevation of the outside replacer; this view may be considered as a section on the line 3—3 of Fig. 1, the upper portions of the cross ties being shown in cross section; Fig. 4 is a cross section on the line 4—4 of Fig. 3; and Fig. 5 is a cross section on the line 5—5 of Fig. 1.

Referring more particularly to the parts, 1 indicates the inside replacer, while 2 indicates the outside replacer. The general form of both of these replacers is very similar. The inside replacer comprises oppositely extending guide arms 3 and 4, the sides 5 whereof are in alinement with each other, and are adapted to be applied to the edge of the rail 6, as indicated in Fig. 1. These guide arms 3 and 4 are quite wide at their outer extremities and taper toward the middle point or transverse axis of the replacer as shown in plan in Fig. 1. Although they taper in this manner as viewed in plan, they taper in an opposite manner, as viewed in elevation in Fig. 3; that is, the outer ends of the arms are thin, and they increase in

thickness in a vertical direction toward the central transverse axis of the replacer. In the upper faces of the guide arms 3 and 4, guide grooves 7 and 8 are formed, and at 60 their lower portions these grooves are formed with flaring mouths 9 and 10 which facilitate the entry of a wheel into the grooves.

At its middle point the replacer 1 is formed with a projecting shoe 11 which extends out over the rail. The under face of this shoe rests upon the head of the rail, and at its outer edge the shoe is formed with a downwardly projecting bead 12, as indicated in Fig. 5. This shoe 11 has its greatest height 65 at the central transverse axis of the replacer, and presents inclined upper faces 13 and 14. These faces 13 and 14 are quite thin at their outer edges. In alinement with the inner side of the head of the rail, the shoe 11 is provided with a longitudinal guide groove 15. Near the right-hand end of this groove 15, the left-hand guide groove 7 merges into it; likewise, near the left-hand end of the groove 15 the groove 8 communicates with the 70 groove 15. In the space between the points of intersection of the grooves 7 and 8 with the groove 15, an elongated projection 16 is formed, which is of triangular form, the triangle having a very long base. 75

As indicated in Fig. 2, the middle portion of the replacer is cored out or formed hollow, so that it presents an inside wall 17 and an outside wall 18. These walls 17 and 18 are connected by transverse webs 19 which are preferably formed integral with the body of the replacer. On the inner sides 5 of the arms which lie near the inner side of the rail 6, pockets 20 are formed which are adapted to receive the braces for the rail chairs. In 80 the construction shown we have represented the replacer as being supported upon three adjacent ties; we therefore provide three pockets 20. In order to make the replacer secure against longitudinal shifting on the 90 rail, we provide its under side with transverse notches or recesses 21 which are adapted to engage the upper faces of the cross ties 22 as shown in Fig. 3. The pockets 20 and the recesses or notches 21 are formed on both 95 of the replacers.

The outside replacer 2 will now be described: The construction of the arms 23 of this replacer is similar to that of the arms 3 and 4; but the guide grooves 24 formed in 100 the upper sides of the arms, are disposed somewhat nearer to the rail 25 than with the

inside replacer; they are provided with flaring mouths 26 which characterize the grooves 7 and 8. This replacer is formed with a shoe 27 which projects out and rests upon the upper face of the rail. This shoe, however, does not overhang the rail by means of a bead such as the bead 12; its inner face 28 simply terminates flush with the inner side of the rail head as indicated in Fig. 1. The arms 23 of this replacer are thin at their outer ends and increase in vertical thickness toward the central axis of the replacer, and the shoe 27 also presents inclined upper faces 29 and 30 which are similar to the inclined upper faces 13 and 14 of the shoe 11. In this replacer we do not provide a longitudinal groove such as the groove 15, but simply arrange the guide grooves 24 so that they intersect on the central axis of the replacer and extend beyond the point of intersection so that they come out upon the ends of the shoe near the inner side of the rail head. The replacers are applied to the rails in the manner indicated in Fig. 1, and the rail truck is advanced in the usual manner so that the wheels will enter the guide grooves 7 and 24 or 8 and 24. The flaring mouths of the grooves insure that the wheels will be guided properly upon the replacer toward the rails. As the wheel passes up the guide groove in the inside replacer, it advances toward the rail and rises to the elevation of the middle point of the replacer. Beyond this point the wheel descends toward the end of the groove and as it approaches the position of the rail, the face of the wheel comes upon the upper face of the shoe 11 so that the shoe supports the weight of the wheel and lets the wheel run down gradually until it comes upon the rail. Of course, the replacer can be used to replace a wheel coming from either direction. If it is desired to pass a wheel which has not been displaced from the track over the replacer, this is permitted by the presence of the bead 15. The advancing wheel simply rolls up on one of the inclined faces 13 or 14 and descends on the opposite face. In replacing the outside wheel the operation is substantially similar to that described, the flange of the wheel advancing in the groove 24 until it reaches the middle point of the replacer, whereupon it begins to descend on the inclined faces of the shoe 27. In this way the flange of the wheel is guided to a point near the side face of the rail and the wheel drops gently into position. By reason of the fact that wheels not displaced from the track may pass the replacer, we are enabled to apply the replacer at the most convenient point found on the track near the scene of the derailment, and this is regarded as an advantage.

Having thus described our invention, we claim as new and desire to secure by Letters Patent:

1. A car replacer having a pair of oppositely extending guide arms with alining sides adapted to be applied to the side of the rail, and having a shoe projecting over the rail and presenting inclined upper faces meeting near the middle transverse axis of said shoe, said arms having guide grooves extending upwardly in the upper faces thereof affording means for guiding the wheels. 65

2. A car replacer having oppositely extending guide arms presenting alining side faces adapted to be applied to the side of the rail, said side faces having pockets therein and having notches on the under side thereof receiving the cross ties, said guide arms having grooves in the upper faces thereof adapted to guide a wheel onto the rail. 75

3. An inside replacer having guide arms and a shoe projecting over the rail, said shoe having a longitudinal guide groove therein alining with the inner side of the rail and adapted to pass an undisplaced wheel rolling on the rail. 80

4. An inside replacer having guide arms inclining downwardly from the middle transverse axis thereof and having grooves on the upper faces of said arms intersecting each other, a shoe projecting over the rail having a longitudinal groove at the side of the rail connecting said guide grooves, said longitudinal groove affording means for passing an undisplaced wheel. 85

5. An outside replacer having oppositely extending guide arms with a shoe projecting therefrom over the rail, said shoe presenting inclined upper faces extending downwardly from the middle transverse axis of the said replacer, said guide arms being inclined and having guide grooves on the upper sides thereof intersecting on said axis and extending down said inclined faces to points near the inner side of the rail. 90

In testimony whereof we have signed our names to this specification in the presence of two subscribing witnesses.
